US0D1073486S

(12) **United States Design Patent** (10) **Patent No.:** **US D1,073,486 S**
(45) **Date of Patent:** **** May 6, 2025**

(54) **TWO-CELL BEVERAGE BOX**

- (71) Applicant: **Pratt Corrugated Holdings, Inc.**, Brookhaven, GA (US)
- (72) Inventors: **Shifeng Chen**, Newport News, VA (US); **Greg Sollie**, Sharpsburg, GA (US); **Jamie Waltermire**, Peachtree City, GA (US)
- (73) Assignee: **Pratt Corrugated Holdings, Inc.**, Brookhaven, GA (US)
- (**) Term: **15 Years**
- (21) Appl. No.: **29/904,959**
- (22) Filed: **Oct. 13, 2023**

Related U.S. Application Data

- (63) Continuation of application No. 29/753,406, filed on Sep. 30, 2020, now Pat. No. Des. 1,007,300.

(57) **CLAIM**

The ornamental design for a two-cell beverage box, as shown and described.

DESCRIPTION

FIG. 1 is a top perspective view of a two-cell beverage box showing the claimed design with a telescoping portion positioned in an extended configuration.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a plan view of the two-cell beverage box shown in a fully collapsed configuration.

FIG. 9 is an elevation view of the two-cell beverage box shown in a partially collapsed configuration.

FIG. 10 is a rear elevation view thereof.

FIG. 11 is a front perspective view of the two-cell beverage box shown with the telescoping portion positioned in a retracted configuration; and,

FIG. 12 is a top perspective view thereof.

Those features shown in broken lines form no part of the claimed design.

1 Claim, 10 Drawing Sheets
